DUMP CAR STRUCTURE

Edwin C. Jackson, St. Louis, Mo., assignor to
General Steel Castings Corporation, Granite
City, Ill., a corporation of Delaware

Application December 5, 1931, Serial No. 579,307

3 Claims. (Cl. 105—271)

This invention relates to railway rolling stock and consists in a novel construction of dump cars of the tilting body type.

An object of the invention is to provide a main underframe for a dump car which will be simpler and more durable than similar structures previously in use.

Another object is to avoid the necessity of mounting the main air reservoir upon brackets projecting from a wall of the under-frame by forming the reservoir within the center sill casting of the main under-frame.

Another object is to combine the body tilting cylinders with the underframe to improve spacing conditions and to strengthen the structure.

These general objects and other more detailed objects are attained in the structure illustrated in the accompanying drawings, in which—

Figure 1 shows at the right a top view of the main under-frame and at the left a portion of the under-framing of the car body mounted thereon.

Figure 2 is in part a side view, and in part a vertical longitudinal section taken on line 2—2 of Figure 1.

Figure 3 is a vertical transverse section taken on a line 3—3 of Figure 1.

Figures 4 and 5 are similar sections taken on corresponding section lines of Figure 1 and showing in broken lines the body in tilted position.

Figure 6 is a detailed side view and vertical longitudinal section on an enlarged scale taken on a line 6—6 of Figure 1.

Figure 7 is a top view on an enlarged scale of the main under-frame structure adjacent the dumping cylinders.

The main under-frame portion of the structure is in many respects similar to that shown and described in Patent No. 1,620,839, issued March 15, 1927 to W. M. Sheehan, and preferably comprises an integral structure including an elongated box section center sill member 1 having flanged draft sills 2 at each end, the latter being preferably provided with integral draft lugs 3.

The inner ends of the draft sills diverge sideways and merge with bolsters 4, each having a horizontal bottom web 4a, top webs 4b sloping downwardly from each side of the center sill, and spaced upright webs 4c. Located at each end of the bolsters are housings 5 for receiving body stop springs 6.

The box-shaped center sill extends through each bolster 4 and forms a reinforcing structure 7, arranged to be mounted upon the usual center plate elements (not shown) on truck 8.

Formed integrally with the center sill between bolsters 4 is a brake cylinder 9 carried by diagonal ribs 10 which with the projecting lower web of the sill form a three-sided hollow cylinder support bracket.

The main under-frame also includes integral upstanding hinge elements 11, located at intervals along the center sill, and body tilting shaft brackets 12. The brackets are disposed in pairs along the under-frame, and at each side of the center sill substantially in alignment with the upright side walls thereof. Each transverse pair of brackets 12 is connected by a rib 13.

Dumping cylinders 25 are formed integral with the center sill, the side wall of each cylinder 15 merging with the adjacent upright wall of the center sill whereby the sill wall forms a part of the cylinder wall, these portions of the walls being of uniform thickness to avoid duplication of metal at this point. The head H of each cylinder is removable and extends radially beyond the cylinder wall in the usual manner. The adjacent portion of the vertical wall of the center sill is recessed for a short distance, as indicated at R, to accommodate the corresponding portion 25 of the cylinder head.

The cylinders 25 are provided with pistons 26 having body engaging extensions 27, the latter being bifurcated at the top to form tripping arms 28. Located within the box section center sill 30 and preferably, but not necessarily, between cylinders 25, are a pair of spaced, dome-shaped partitions forming with the center sill webs a main air reservoir 29.

The car body framing comprises a one piece 35 casting including side sills 14, end sills 15, all of channel section, and intermediate longitudinal sills 16, center sills 17, and transoms 18, all of I section. Depending from the center sills 17 at intervals are body hinge elements 19 for cooperating with under-frame hinge elements 11 to support the body. Dumping cams 20 include lobes 20a and 20b. Side bearing arms 21 and body stop pads 22 are located immediately beneath the intersections of the associated transoms 18 and the longitudinal members 16 and are integral therewith. Renewable wear plates 22a are applied to the faces of the pads 22.

The body structure is preferably provided with reinforced swinging side doors 36 and suitable hinge and latch elements (not shown). The body tilting mechanism, portions of which are illustrated in Figures 4 and 5, is old and in itself does not constitute the present invention. Briefly described, this mechanism includes coordinat-

ing longitudinal shafts 23 extending along the under-frame from bolster to bolster and supported in brackets 12. Secured to these shafts between corresponding transverse pairs of brackets 12 are trip dogs 24, each located in the path of the corresponding tripping arm 28. Attached to the shafts 23, adjacent each side bearing arm 21, is a weighted lever 30 which is connected through links 31 and 32, with the side bearing support member 33 on the opposite side of the sill, swingably mounted on lugs 35 adjacent housing 5 at the end of the bolster.

In operation of the dumping mechanism, air is forced into the pair of dumping cylinders on either side to tilt the body. As arms 28 move upwardly and engage the corresponding dogs 24, shafts 23 on that side are rotated causing the side bearing supports 33 connected therewith to be swung sidewardly by means of mechanism not shown. The swung positions of supports 33 are shown in broken lines in Figure 5. Continued upward movement of the operating pistons causes extensions 27 to engage the lower lobes 20a of the corresponding cams 20, to effect the tilting of the body. The side bearing arms on the descending side of the body pass through openings 4d in the top webs 4b of bolsters 4.

In the extreme tilted position, the wear plates 22a on stop pads 22 on the lower side of the body engage buffers 34 yieldingly supported on springs 6 in housings 5, and, as indicated in broken lines on the left hand side of Figure 4, the higher lobes 20b, of cams 20, engage the corresponding operating piston extensions 27.

To return the body to horizontal, air is simultaneously released from the filled cylinders and admitted to the emptied cylinders. As the emptied cylinders are filled, their tripping arms 28 strike the corresponding dogs 24, causing the bearing supports 33 on each side to be returned to normal position.

Obviously, the invention is not limited to the exact details of the structures illustrated and

described. For instance, the general shape of the main under-frame, as well as the body under-frame, are not essential. Moreover, the various hinge elements and brackets may be varied as to shaping and position, and as to the particular number of the elements used, without departing from the spirit of the invention. The exclusive use of all such modifications as come within the scope of the appended claims is contemplated.

What is claimed is:

1. A railway dump car integral structure including a center sill having an upright web and a bottom web, and an upwardly disposed body tilting cylinder merging with said upright web, 15 said webs and the cylinder wall being of uniform thickness to facilitate casting and said bottom web extending around and merging with a portion of said cylinder and bracing the same.

2. A railway vehicle underframe center sill of 20 general rectangular section, and a fluid cylinder extending along a wall thereof and with its wall merging with said sill wall, a portion of said sill wall adjacent an end of said cylinder being recessed to permit application to said cylinder of 25 a cylinder head projecting radially of the cylinder beyond the merged portions of said walls shaped to extend outwardly of said merged walls.

3. A railway dump car integral structure including a sill having an upright web and top and bottom webs, and a body tilting cylinder merging with said upright web, a portion of the web forming a portion of the cylinder wall, the top of said cylinder being beneath said sill top web and portions of said sill upright and 30 top webs adjacent said cylinder being recessed to accommodate a removable cylinder head which projects beyond the side wall of the cylinder to permit application of the head to the portion of the cylinder wall which merges with said sill 35 upright web.

EDWIN C. JACKSON.
